UNITED STATES PATENT OFFICE.

CHARLES VAN DYKE HILL, OF ST. LOUIS, MISSOURI.

RADIATOR-SHELF.

1,116,730.

Specification of Letters Patent.

Patented Nov. 10, 1914.

Application filed April 17, 1913. Serial No. 761,840.

To all whom it may concern:

Be it known that I, CHARLES VAN DYKE HILL, a citizen of the United States, residing at St. Louis, Missouri, have invented a certain new and useful Improvement in Radiator-Shelves, of which the following is a full, clear, and exact description, such as will enable others skilled in the art to which it appertains to make and use the same, reference being had to the accompanying drawings, forming part of this specification, in which—

Figure 1 is a front elevational view of a combined radiator shelf and shield of my improved construction. Fig. 2 is a vertical sectional view taken approximately on the line 2—2 of Fig. 1. Fig. 3 is an enlarged horizontal section taken approximately on the line 3—3 of Fig. 2. Fig. 4 is a perspective view of one of the shelf supporting blocks and its attaching bracket. Fig. 5 is an enlarged detail section taken approximately on the line 5—5 of Fig. 2.

My invention relates to a combined shelf and shield for radiators, the principal object of my invention being to construct a comparatively simple, inexpensive fixture in the form of a shelf and an air and dust shield which can be easily and quickly applied to or removed from an ordinary radiator, and which fixture, when properly applied for use, forms a substantial, rigid shelf of ample area on top of the radiator, and the shield portion of which fixture extends downward from the shelf to the rear of the radiator for the purpose of deflecting air and dust carried thereby outwardly away from the wall which is adjacent to said radiator, thereby preventing discoloration of said wall by reason of the heated dust-laden air which rises from the radiator.

Further objects of my invention are to construct a strong, substantial shelf of material which will not be affected by the heat from the radiator, to provide a fixture which can be easily and quickly applied to or removed from a radiator by means of a single tool such as a screw-driver, to provide means whereby the fixture is rigidly attached to the radiator, and to provide means for maintaining the lower edge of the shield in contact with the wall directly behind the radiator so that practically all the heated air arising from said radiator will be deflected outwardly, thereby preventing discoloration

of the wall to the rear and above the radiator.

To the above purposes my invention consists in certain novel features of construction and arrangement of parts hereinafter more fully described and claimed.

In the construction of my improved shelf and shield I make use of one or more supporting blocks 10, the same being preferably formed of seasoned wood, and attached in any suitable manner to the underside of each block is the horizontally disposed leg of an angle bracket 11, the vertically disposed leg of which extends downward between an adjacent pair of sections of the radiator A, and formed in the lower portion of this vertically disposed leg is an aperture 12. The rear upper corner of each block is preferably rabbeted, as designated by 13, to form sufficient space for a portion of the shield forming a part of my improved fixture and hereinafter more fully described. In some instances it may be found desirable to form slots in the rear portions of the blocks 10, as shown by dotted lines in Fig. 4, for the accommodation of the upper edge of the shield.

Where the radiator is comparatively short or formed of but few sections it is only necessary to use one of the supporting blocks 10 and its angle bracket, but where said radiator is of considerable length, it is desirable to use two or more of the blocks, as shown in Fig. 1. The means for attaching each block and its angle bracket to the radiator comprises a screw rod 14 which passes through a block 15, which latter bears against an adjacent pair of the sections of the radiator, and the rear end of this screw rod passes through the aperture 12 in the lower end of the angle bracket 11, and said rear end is threaded and receives a nut 16.

The block 10 rests directly on the upper ends of an adjacent series of the radiator sections, and when the screw rod 14 is tightened by means of a tool such as a screw-driver, the lower portion of the angle bracket and the block 15 are drawn toward each other in such a manner as to tightly engage and rigidly clamp an adjacent pair of the radiator sections, thus firmly and rigidly anchoring the block in proper position on the radiator.

The shield 17 forming a part of my improved fixture is preferably constructed of

5 a rectangular section of sheet metal, the
6 same being slightly longer than the radiator
7 to which the fixture is attached and of suffi-
8 cient height to extend down behind the ra-
9 diator a distance of one-fourth or one-third
10 the height thereof. The main body portion
11 of this shield occupies a substantially verti-
12 cal position behind the upper portion of the
13 radiator, and the upper end of said shield
14 is bent to as to occupy a substantially hori-
15 zontal plane, and the front edge of this bent
16 portion fits snugly in the rabbets or slots
17 formed in the rear portions of the blocks 10.
18 Applied to the lower edge of this shield and
19 on the rear side thereof, is a strip or section
20 of material such as asbestos which nor-
21 mally engages directly against the wall to
22 the rear of the radiator. The means utilized
23 for maintaining the lower edge of this shield
24 against the wall comprises one or more
25 screw bolts 19 which are screw-seated in
26 small blocks 20, which latter are adapted to
27 engage against an adjacent pair of the ra-
28 diator sections, and the forward ends of
29 these screw bolts engage directly against the
30 lower edge of the shield 17. When these
31 screw bolts are tightened by means of a
32 screw-driver the blocks 20 are caused to bear
33 against a pair of the radiator sections, and
34 the forward ends of said screw rods bear
35 against the lower edge of the shield and
36 forces the same into contact with the wall.
37 Thus practically all of the heated air rising
38 from the radiator, together with the dust
39 carried by said air, will be deflected out-
40 ward of the upper end of the radiator, and
41 the said heated air and dust will be pre-
42 vented from passing upwardly along the
43 wall immediately to the rear of the radiator.
44 The shelf 21 forming a part of my im-
45 proved fixture is preferably constructed of
46 a composition which includes asbestos and
47 charcoal, any material which is not affected
48 by a normal degree of heat such as is given
49 off from an ordinary radiator. This shelf
50 is preferably rectangular in form, and is ap-
51 plied and fixed to the blocks 10 in any suit-
52 able manner, preferably by means of screws.
53 When this shelf is applied to the blocks it
54 overlies that portion of the shield occupying
55 the rabbets 18 or slots in the blocks 10, and
56 thus the upper portion of said shield is
57 truly located between said shelf and blocks.
58 A combined shelf and shield of my im-
59 proved construction is comparatively sim-
60 ple, can be readily applied to or removed
61 from a radiator, presents a neat and finished
62 appearance, prevents the wall and hang-
63

64 ings immediately above and to the rear of
65 the radiator from becoming discolored by
66 reason of the dust-laden air which ordi-
67 narily rises from a radiator, and the shelf
68 forming a part of the fixture provides a firm
69 and substantial support for all articles of
70 household, store and office use which are
71 ordinarily placed on stands, tables, counters,
72 desks and the like.

73 Ordinarily in the warmer months of the
74 year radiators are entirely useless and do
75 nothing more than to take up floor space,
76 but by combining a fixture of my improved
77 construction with a radiator the same serves
78 a useful purpose during the time it is not
79 in use as a heater for the reason that it
80 forms a strong and substantial base for the
81 shelf.

82 It will be readily understood that minor
83 changes in the size, form and construction
84 of the various parts of my improved ra-
85 diator shield can be made and substituted for
86 those herein shown and described without
87 departing from the spirit of my invention,
88 the scope of which is set forth in the ap-
89 pended claims.

90 I claim:

91 1. The combination with a radiator, of a
92 combined support and bracket detachably
93 connected to the radiator, and positioned on
94 the top thereof, which combined support
95 and bracket is provided in its rear upper
96 portion with a recess, a deflector arranged
97 behind the radiator, the upper edge of which
98 deflector overlies the rear portion of the
99 combined support and bracket and occupies
100 the recess therein, and a shelf positioned
101 upon the combined support and bracket,
102 which shelf engages that portion of the de-
103 flector within the recess and clamps said en-
104 gaged portion against the combined support
105 and bracket.

106 2. The herein-described radiator shelf com-
107 prising a combined support and bracket
108 adapted to be applied to a radiator, a shelf
109 positioned upon said combined support and
110 bracket and arranged above the radiator, and
111 a deflector arranged beneath and de-
112 pending from the rear portion of the shelf,
113 the upper edge of which deflector is clamped
114 between the shelf and support.

115 In testimony whereof I hereunto affix my
116 signature in the presence of two witnesses,
117 this 7th day of April, 1913.

CHARLES VAN DYKE HILL.
